[57] CLAIM

The ornamental design for a medallion, as shown and described.

DESCRIPTION

FIG. 1 is a bottom/front/right side perspective view of a medallion showing my new design;

FIG. 2 is a front elevational view thereof;

FIG. 3 is a rear elevational view thereof;

FIG. 4 is a right side elevational view thereof, the left side elevational view being a mirror image and, therefore, not shown;

FIG. 5 is a cross-sectional view taken along the line V-V of FIG. 3;

FIG. 6 is a top plan view of the medallion shown in FIG. 1; and,

FIG. 7 is a bottom plan view of the medallion shown in FIG. 1.
